Application May 11, 1953, Serial No. 353,997

10

13 Claims. (Cl. 112—36)

This invention relates to improvements in machines for sewing together the parts of a slip-lasted shoe while the edges of its parts are being brought progressively into register, the entire upper of the shoe being given a rough shoe formation at the same time. An example of a machine for performing this type of work is disclosed in United States Letters Patent No. 2,695,579, granted November 30, 1954, on an application filed in the name of Ralph E. Pearsall.

The usual practice in the manufacture of a slip-lasted shoe includes the provision of a flat blank upper cut with an accurate pattern designed to form a shoe when its edges are brought into register with those of an unchanneled blank of relatively thin flexible woven sheet material shaped to correspond with the sole of the shoe. In bringing the edges of the parts into register some force is required to overcome the resistance offered by the material operated upon against deforming it from its natural flat condition. Considerable force and skill are required in sewing together the shoe parts while operating along the abrupt curvature at the toe of a shoe. Great difficulty often is encountered in sewing the inside shank portion of a high-arch woman's shoe.

A desirable type of lock stitch sewing machine for use in the manufacture of slip lasted shoes is a commercially available straight needle machine having a vertical work supporting post. The post has mounted at its upper end a shuttle rotating about an axis at right angles to the work supporting surface on the post, the lock stitch form of seam being necessary to reduce the bulk of exposed thread in a seam to a minimum, especially when a platform cover or wrapper strip or its equivalent enter into the construction.

An important advantage of a vertical post type lock stitch machine is in the arrangement of the shuttle, the work supporting and clamping members on the post. The post also provides at its left side a vertical clearance drop of a depth greater than the side height of a shoe upper so that no interference is met during angular positioning movements of the deformed shoe parts. Such clearance drop is essential where accurate register of the shoe parts is necessary and where a relative elongation or compression along the edges of the parts is to be avoided.

For convenience in manufacture, and for facility in exact adjustment of the parts about the operating point in a post type lock stitch sewing machine, the post is constructed in two parts in the form of brackets independently mounted on a flat bed portion of a main machine frame. One bracket provides means for mounting bearings for the shuttle and for a thread case actuating finger and the other bracket provides mounting means for a work supporting and clamping surface and for a four motion feed dog having a close fitting eye through which the needle passes after penetrating the work, the eye providing an accurate guide for the needle beneath the work. The needle itself is supported for reciprocation in an overhanging arm forming a part of the main machine frame. The length of the arm and the accuracy required in lining

2

up the needle with the guide eye in the feed dog necessitates, for machine assembly purposes, a conveniently adjustable connection between the work support bracket and the main frame. The shuttle bracket also is adjustable on the main frame, independently of the work support bracket to enable positioning the beak of the shuttle where it will enter with certainty into each loop of thread carried through the work by the needle, the shuttle beak passing as close as possible to the needle in entering each loop of needle thread.

For preventing release of the shoe parts in the machine during sewing, and for assisting the feed, this type of machine as constructed without the Pearsall invention is provided with two alternately acting work clamps.

The work clamps comprise the work support and a nonfeeding presser foot on the one hand and the feed dog and a feeding presser foot on the other hand. The ordinary arrangements of these clamps are such that the nonfeeding one engages the work along the left side of the sewing point while the feeding one engages the work at a location immediately surrounding the sewing point. The prior stationary nonfeeding work clamp engages such a span of clamped work surface along the work support lengthwise of the line of the seam and such a projection transversely of the seam line that effective shoe sewing operations are rendered difficult.

To reduce the lengthwise span of the work clamps or the transverse projection, the illustrated machine is constructed with a stationary nonfeeding work clamp having its work engaging surfaces limited with respect to the direction of feed to a gripping area on the work in advance only, of the work feeding clamp, and both clamps are arranged to engage the work serially in the line of the seam as disclosed in the Pearsall patent, instead of extending beyond the sewing point or projecting transversely of it to the left as heretofore. Even with this limitation of clamping area in advance only of the sewing point a sharply curved section of a shoe engaged by work supporting surface on a post type machine still has too short a radius of curvature for easy natural feeding and positioning movements required for effectively sewing a high-arch slip-lasted shoe. Also, the force required to deform the material operated upon from its natural flat condition is so great that even the reduced span of gripping area along the work support is insufficient to prevent elongation and relative contraction between the parts of a shoe in advance of the sewing point, so that the parts still remain excessively stressed with relation to each other while being sewn together and, accordingly, are distorted in certain sections along their edges after sewing. While distorted sections frequently can be smoothed by hot ironing and pressure the incidence of crippled shoes and the requirements for repairing crippled shoes from this cause have always resulted in serious losses to the manufacturers of such shoes.

The difficulties above noted are greatly increased where an attempt is made to sew a slip-lasted shoe upper to a sock lining in a high-arch shoe with a platform sole attached to the sock lining before the sewing operation is started. In this circumstance the platform sole is used as a guide for shaping both the seam and the resulting shoe but its added stiffness increases the resistance offered by the sock lining against deformation from its natural flat condition to such an extent that no sewing machine heretofore constructed has been demonstrated as being capable of sewing such shoe satisfactorily and with uniformly acceptable results.

The objects of the present invention are to provide a shoe-sewing machine of the double clamp and feed type referred to, on which a high-arch slip-lasted shoe may be sewed with more effective and uniform results and

with less effort and skill on the part of the operator than has been required heretofore.

Another object of the invention is to provide a post type machine for sewing the parts of a high-arch slip-lasted shoe in which a platform sole is attached to a 5 sock lining before sewing, with the use of which machine the incidence of cripples and shoe repair requirements are negligible. A still further object is to provide a shoe sewing machine of the type referred to which is more readily adjustable for the purposes intended and 10 more durable in use than prior machines of the same type.

The illustrated embodiment of the present invention comprises a post type, straight needle, lock stitch sewing machine for uniting the registering edges of a shoe upper and a sole member unsupported on a last, which machine overcomes all the objections and difficulties enumerated above, particularly in the provision of a horizontal work gripping abutment at the upper end of its work supporting post, comprising one member in one 15 of a pair of clamps, the abutment having a horizontal portion engaging the sewed section of the work beyond the needle and being formed with a work engaging span along the seam line beyond the needle of less than one-quarter of an inch and with an abrupt drop of a depth 20 greater than the side height of the shoe upper operated upon at the end of the span beyond the needle to clear the downwardly curving sections of the shoe parts in order that the shoe parts being operated upon may flex 25 away from each other readily with an angular formation during sewing, the parts hinging about the sewed portion of the seam. With this feature of the invention the abutment has a shoe engaging projection extending transversely of the seam line a distance of less than one-eighth of an inch. As illustrated the abutment surface 30 has a total length of work engaging span, both in advance of and beyond the sewing point of the needle of less than one-half of an inch so that the smallest radius of curvature through which the edges of the parts are bent may be readily accommodated in the smallest size 35 of shoe to be made with a high arch.

The reduction in shoe engaging span and of transverse projection of the work supporting post is accomplished, in accordance with the invention, by changing the construction in a unique manner at the upper end of the work supporting and clamping bracket while retaining the shuttle mounting bracket without modification, thus preserving all of the essential adjustment requirements in the machine so that effective sewing operations may be performed while the structural design of the machine remains in compliance with mass production and manufacturing requirements.

These and other features of the invention, as herein-after described and claimed, will readily be apparent from the following detailed specification taken in connection with the accompanying drawings, in which:

Fig. 31 is a perspective view of the work supporting post and operating devices in the improved machine illustrating the manner of operation on a left high-arch shoe.

The apparatus illustrated in the drawings is a straight needle lock stitch sewing machine with eye-pointed needle, double clamp and feed and a post type work support adapted for operation upon the marginal portions of a slip-lasted shoe composed of flexible material cut to a 75 carefully designed pattern in flat blank form to provide a

configuration of a shoe when the edges of the blank parts are brought into registering relationship. During operation of the machine the edges of the parts are manipulated by the operator progressively just in advance of the sewing point to bring them into register for progressive permanent attachment. The machine is characterized by an unusual ease with which shoe parts are manipulated during sewing with better results than those obtainable with prior machines. While operating upon the edges of the parts in a conventional form of slip-lasted shoe, the machine demonstrates its advantages, and more particularly, while sewing the type of shoe identified in Fig. 12 of United States Letters Patent No. 2,425,420, granted August 12, 1947, and in No. 2,546,152, granted March 27, 1951, upon application of J. D. Chandler.

The shoe disclosed in Patent No. 2,546,152 is of the type in which a sock lining has attached to it a pre-cut platform sole of smaller size than the sock lining and the upper is secured to the sock lining by a seam running along outside the edge of the platform sole and passing through the sock lining and upper only, without including the platform sole in the seam. This type of shoe construction is desirable because it enables the edge of the platform sole to be employed as a guiding surface for the seam. The platform sole being relatively stiff, serves in maintaining the resulting shoe in accurate conformity with the outline of the sole and avoids the necessity of a subsequent operation for individually fitting the platform sole to an irregular outline of a seam connecting the upper to the sock lining.

The configuration of the Chandler shoe is to a large degree determined with respect to its uniformity in contour and appearance, upon the manner of guiding and positioning the parts during the process of sewing their edges together. For producing the best results the parts of the shoe are strained during the sewing operation to introduce into each part a stress equal to that introduced into the other part and in so doing the shoe must be twisted and deformed as the operation progresses, particularly along those sections of the shoe beyond the sewing point which are secured together by the completed stitches of the seam. In advance of the sewing point, the parts being still disconnected, the twisting and deforming movements need not be so pronounced. If the strain in the shoe upper is greater than that in the sock lining, excessive deformation is evidenced by localized wrinkles. These wrinkles require special treatment to remove, and frequently result in second grade or crippled shoes. In many instances wrinkles may be removed by heat and pressure but in so doing there is danger of weakening the construction to an extent such that difficulties are met during subsequent manufacturing operations and the durability of the completed shoe may seriously be impaired.

Proper twisting and deforming movements of a slip-lasted shoe during sewing operations is particularly important when operating upon high-arch shoes having abrupt lengthwise curvatures along their edges, it being necessary to provide sufficient clearances about the operating point of the machine for movements of the curved edges. The machine of the Pearsall patent provides an improved construction for sewing slip-lasted shoes with a lock stitch seam by reducing the clamped section along a seam connecting the edges of shoe parts beyond the sewing point. The benefit obtained in the Pearsall machine is most pronounced along the toe portion of a shoe where the greatest curvatures of the edges occur. With a high-arch shoe having curvatures of short radius along their inside shank portions, the length of the clamped section at the sewing point must not only be reduced but also substantial clearances equal to the side height of their uppers are needed to permit the parts of the shoe to assume their natural curvatures with equally distributed stress between them. Furthermore, the sock lining of the Chandler shoe having already attached to it a pre-cut platform sole is substantially stiffer than the upper so that a greater amount

of force must be applied to the upper than to the platform sole during the sewing operation. Accordingly, the shoe is not presented to the machine with the upper projecting upwardly from the work support, as illustrated in the Pearsall patent where the sock lining is not reinforced by a platform sole, but the shoe during the illustrated sewing operation projects with the major portion of its upper extending downwardly from the level of the work support, this being the natural relationship of the shoe parts while being brought into register in the machine. For this reason the work clamps below as well as those above the work must have a limited span in the direction of work feed.

Referring more particularly to Fig. 20 of the drawings, the parts surrounding the sewing point and corresponding to those of the Pearsall machine are illustrated as including an eye-pointed needle 2, a stationary work support plate 4, forming one member of a nonfeeding clamp and being secured to a work support bracket 6, a nonfeeding presser foot 8 forming the other member of the nonfeeding clamp and engaging the work support plate 4 along the line of feed in advance of the sewing point and a work feeding presser foot 10 forming a member of a feed clamp and acting to grip the work against a feed dog 12 moving in unison therewith and extending through a slot in the work support plate. The gripping and feeding clamps are located to engage the work serially along the margin of the sock lining. While such an arrangement of work gripping and feeding clamps is desirable in operating upon a relatively flexible sock lining with no platform sole attached, the span of the work support plate along the line of work feed is so long that it prevents the upper of a shoe from assuming its proper curvature with relation to a sock lining when a platform sole is attached thereto before sewing, the platform sole preventing the sock lining from assuming a sufficiently deformed shape on the work support, thus forcing the upper of the shoe to assume most of the deformation required in bringing the edges of the parts into register below the level of the work support.

When an attempt is made to sew a high-arch slip-lasted shoe for a right foot having an upper 14, a sock lining 16, and a pre-cut platform sole 18 attached to the sock lining on the Pearsall machine, the parts assume the positions illustrated in Fig. 21, the broken outline indicating the flat position of the platform sole and the full outline of the sole indicating its partially deformed position just before the sewing operations reach the inside curvature of the shank. When this sewing position is reached, it is apparent that the edge of the upper 14 in advance of the needle diverges substantially from the line of the sock lining. As the sewing progresses, the edge of the upper is brought into register with the edge of the sock lining, the platform sole 18 being cut with a slightly smaller size than the sock lining so as to provide a sewing margin not over one-eighth of an inch in width. As the edges are brought into register substantial deformation occurs and when the greatest curvature is reached on the inside of the shank, as indicated in Fig. 22, the greatest resistance to deformation is offered, the span of the work support plate 4 preventing the parts from assuming their proper curvatures. As a result, the edges of the parts are excessively stressed and distorted, the sewing operation securing their edges together in a progressively distorted relationship. Fig. 22 shows the effect of distortion as it causes the platform to bulge at 20, contraction wrinkles 22 being formed (see Fig. 23) in the underlying edge of the upper while being forced into register with the edge of the sock lining. As the sock lining is sewn to the upper the wrinkles in the upper are flattened, but the platform sole is raised sufficiently to cause partial separation from the sock lining. Also, the distortion wrinkles are permanently retained by the stitches.

The shoe resulting from such sewing operation is illustrated in Fig. 24 with a gaping relationship between the

sock lining and the platform sole readily apparent. When a last 24, shown in Fig. 25, is inserted in the shoe the wrinkles 22 are greatly extended upwardly from the sock lining to prevent a close fit with the last. Some success has been obtained in removing these wrinkles through hot ironing or steaming, but efforts to repair them are not always successful and these efforts always increase the time and expense of shoe manufacture.

In sewing a shoe for the left foot a different form of difficulty arises. In a left shoe it is the practice to sew the inside of the arch first, the parts otherwise being presented in the same manner to the sewing machine.

Referring to Fig. 26 when the sewing operation reaches the inside of the left shoe illustrated, sufficient distortion of the parts occurs to separate the sock lining, indicated at 25, partially from the attached platform sole 26, forming a wrinkle 27 in the sock lining defining the separated portion. The upper of the left shoe thus sewn is indicated at 28. As the sewing operation continues to completion the parts are otherwise brought into shape, little or no difficulty being experienced with the seam along the outside of the shank where less curvature occurs. The outside appearance of the separated portions of the sock lining and platform sole is shown in Fig. 27. For the reason that the parts are sewn in this relationship permanent distortion results in the completed shoe, necessitating more or less adjustment or repair before subsequent operations.

The work support post of the machine embodying the present invention has the gripping area of its work engaging and clamping surfaces limited along the margins of the parts operated upon to permit sewing a high-arch shoe having a platform sole 29 (see Figs. 29, 30 and 31) attached to its sock lining 30 in such a way that the stresses are equally distributed throughout the registering edges without imparting excessive local distortion, either in the sock lining or its upper 31 during sewing, particularly along the inside shoe shank. The machine also is equipped with all of the devices and clearance spaces needed for close margin slip-lasted shoe sewing with a lock stitch seam including a shuttle, two alternately acting work clamps engaging and gripping the edges of the shoe parts serially along the line of a seam being inserted to grip and feed the parts, and for this purpose the upper end of the work support post is cut away to provide a stationary abutment of restricted surface area comprising one member of one of the clamps with a horizontal surface engaging the sewed section of the shoe parts formed with a span along the seam line beyond the needle of less than one-quarter of an inch and with an abrupt drop of a depth greater than the side height of the shoe upper at the end of the span beyond the needle to clear downwardly curving sections of the shoe parts. For purposes of illustration the angle from the horizontal for the abrupt drop is shown to be substantially greater than 45° and preferably approaches 90°. By this cut-away construction a downwardly curving section of the shoe upper 31 is enabled to assume its natural shape while sewing along the inside shank of the shoe, as best shown in Figs. 3 and 29. It has been found in practice that a span beyond the needle of greater than one-quarter of an inch in this direction obstructs the proper curvature of the parts, especially with feeding and nonfeeding alternately acting work clamps arranged serially along the line of a seam being inserted.

A further restriction in the area of the work engaged by the work clamps also is highly desirable. Since the sock lining 30 seldom projects beyond the platform sole more than one-eighth of an inch, the shoe gripping abutment at the upper end of the post is formed with a shoe engaging projection extending transversely of the seam line a distance of less than one-eighth of an inch beyond the point of needle operation and also with an abrupt drop to clear downwardly curving sections of the upper as it separates with an angular deflection from the sock lining

with a hinge action about the stitches already inserted, as best shown in Fig. 4. If a transverse projection of the work supporting surface on the post is greater than one-eighth of an inch, deflection of the upper and improper curvature of the shoe parts causes excessive deformation and corresponding damage to the resulting shoe. With a relatively narrow sewing margin of one-eighth of an inch between the edge of the sock lining and the platform sole, it is essential for the grip of the work clamps to extend at either side of the seam line. The benefits and advantages of a work engaging abutment formed with a restricted work engaging surface both along the seam line and transversely thereof are obtained in the illustrated lock stitch post type sewing machine by a unique construction readily applicable to existing double clamp and feed machines without detracting from other requirements of adjustability and alinement of the machine frame structure.

The work support post of the illustrated machine is constructed in a known manner with two vertical brackets 32 and 39 mounted for individual adjustment in parallel side-by-side relation on the flat bed portion 37 of the main machine frame. In accordance with the usual construction, the work support bracket 32 is slidable adjustably in a rectangular groove 34 extending transversely to the seam line and is secured in fixed position along the groove by screws 35 extending through enlarged counterbored openings in the bed portion 37 and into threaded engagement with the bracket 32 and an angle plate 36 bolted to the vertical side of the bracket. When the screws 35 are loosened, the bracket 32 may be moved to bring the needle into the desired relationship with the work clamps and with the transverse projection of the abutment secured to the upper end of the bracket 32. The shuttle bracket 39 is mounted for similar attachment in the rectangular groove 34 and is secured in adjusted position by a pair of clamp screws 38 passing through counterbored openings in the bed plate and into threaded engagement with a horizontal flanged portion of the bracket.

As in the Pearsall machine the work is gripped alternately first by a nonfeeding clamp and then by a feeding clamp arranged to engage the sock lining and upper serially along the seam line. The feeding clamp comprises a feed dog 40 mounted in the bracket 32 and secured to the upper end of a vertical lever 42, a central slot in which is engaged by a block 44 pivotally mounted on a screw stud 46 threaded into the bracket 32 (see Figs. 1 and 6). The lower end of the feed lever 42 is pivotally connected with a feed bar 47 having secured to it an actuating yoke 48, the yoke portion of which surrounds an eccentric 50 driven in unison with the operation of the stitch-forming devices and a horizontal arm of which is connected to an arm of a lever 52 including a shaft 54 to which it is secured, the other arm of the lever being actuated by mechanism timed to impart the proper feeding movements to the work. The feed dog 40 is constructed at its upper end with a needle guiding opening 56 (see Fig. 10), which of necessity must be accurately alined with the needle 2. The adjustable mounting of the bracket 32 enables proper alinement to be obtained in spite of manufacturing inequalities.

The shuttle bracket 39 is ordinarily the same height as the work support and feed dog bracket 32 but is entirely separate from it and carries bearings 58 (Fig. 4) for a vertical shuttle supporting shaft 60 to the upper end of which the shuttle, indicated at 62, is made fast. The shuttle 62 has a beak 64, the path of which must be brought into intersection with the thread carried by the needle 2 while the needle engages the work. Also the upper bearing 58 has threaded into it a screw stud 65 passing loosely through a thread case engaging finger 66 actuated in timed relation with the rotation of the shuttle to engage and disengage a thread case 68 mounted for relative rotation in the shuttle.

The improved work engaging abutment of the present invention is applied to the upper ends of a pair of spaced vertical arms on the bracket 32 which are cut off shorter at their upper ends than the shuttle bracket to receive the abutment (see Figs. 6 and 8). The abutment is constructed as a V-shaped member 70 having its smaller end uppermost provided with a feed dog receiving slot 72 (Fig. 7) and with inclined sides forming abrupt drops surrounding the feed dog 40. Between the lower ends of the inclined sides of the abutment is a strut portion 73 connecting perforated enlarged lower ends of the abutment for receiving a pair of clamp screws 74 entering into threaded relation with the upper ends of the vertical arms on the bracket 32. The rearmost vertical arm of the bracket 32 is not entirely cut away but includes a vertically projecting spindle 76 (see Fig. 6) for a purpose to be described.

The shuttle supporting bracket 39 has a shuttle enclosing portion at its upper end of the same dimension horizontally in the direction of the seam as the feed dog supporting bracket 32. In order to provide increased clearance spaces both in advance of and beyond the sewing point in the machine for the sewed portions of the shoe parts and for the operator's fingers in grasping the parts, the post is provided with vertically extending angular recesses 78 and 80 (see Figs. 2, 5 and 6) including abrupt drops at the forward and rear ends of the abutment of greater width transverse to the seam line at the lower portion of the bracket 32 beneath the shuttle than at the upper portion of the bracket 32 near the work engaging surface of the abutment. The additional transverse width of the recesses is accommodated below the shuttle and upper bearing 58. Enclosing the two post brackets 32 and 39 are a pair of side plates 79 fitting the general configuration of the brackets and secured along their edges to the shuttle bracket 32. The rearward side plate 79 is supported at its upper end in part by the spindle 76 on the bracket 32 to prevent accidental contact with the pointed beak of the shuttle 62.

While not as essential in avoiding excessive distortion in the manufacture of high-arch slip-lasted shoes as a short dimension of the work engaging abutment beyond the sewing point of less than one-quarter of an inch, a similar dimension in advance of the sewing point also is of assistance to enable the operator to guide the parts as close as possible to the sewing point. Accordingly, the full length of the work engaging surface on the abutment along the seam line is made with a total dimension of less than one-half of an inch. A supporting surface dimension of less than one-quarter of an inch in advance of the sewing point is of advantage in positioning the parts of a shoe with their edges in register throughout a greater distance in advance of the sewing point than is possible without the short advance dimension. It is possible accordingly for the operator to deform the parts readily in advance of the sewing point to an extent equal to that beyond the sewing point and to provide space for the operator's fingers closer to the sewing point than heretofore available in this type of machine.

With the present construction of the work engaging abutment member 70 (see Fig. 28) high-arch right shoe parts are brought easily into conformity with smooth curvatures and without excessive distortion as illustrated in Fig. 29 before the inside shank of the shoe is reached. The sewing operation may then be brought to completion with uniformly desirable results. As illustrated in Fig. 30, it is evident that the completed shoe is free from separations between its sock lining and platform sole and after application of the shoe to a last accurate conformity is insured. In sewing a left shoe composed of a platform sole 81, a sock lining 82 and an upper 83 (Fig. 31) the same benefits are obtained while operating along the inside of the arch.

To assist further in guiding the parts properly and to avoid the possibility of the platform sole in a shoe coming

into contact with the needle, the nonfeeding presser foot, indicated at 84, is provided with a horizontal nib 85 (Fig. 12) projecting transversely at one side only from the line of the seam inserted by the needle, at a distance above the work clamping surface of the non-feeding foot and above the work engaging surface of the work support equal to the thickness of the platform sole. The edge of the platform sole is guided by engagement with the lower end of the presser foot 84. The nib holds a portion along the margin of the platform sole adjacent to the guided edge in a horizontal position, causing the sole to bend a short distance from the edge (see Figs. 4 and 8). In this way flexure of the sock lining 82 at the edge of the platform sole 81 is avoided and the needle is able to pass in close parallel relation to the edge of the sole without engaging it.

For guiding the edge of the upper operated upon the illustrated machine is equipped with a yieldingly mounted upper gage 86 located at one side of the seam line and 20 slidingly supported on the machine frame in a vertical guideway of a bracket 88. The bracket 88 has a vertical slot 90 (see Fig. 4) through which passes a stud 92 entering into threaded engagement with the edge gage. Between the upper end of the slot 90 and the stud 92 is a 25 compression spring 94 acting yieldingly to press the edge gage in a downward direction toward the work supporting abutment. To limit the downward movement of the upper gage, the bracket has threaded into it a vertical stop screw 95 arranged to engage the stud 90 in its lowermost position.

For moving the upper gage toward and from the needle to vary the margin of the seam, the bracket 88 has a horizontal groove into which fits the rib of a mounting plate 96 (see Figs. 3, 4, 14 and 15) secured to the overhanging arm of the machine frame by a pair of clamp screws 98. The bracket 88 also has a vertical notch into which enters a collar 100 (see Fig. 14) on a thumb screw 102, the thumb screw being threaded into a horizontal passage in the mounting plate 96. To hold the bracket 30 88 in position on the rib of the mounting plate 96 the bracket is slotted to receive a screw 103 threaded into the mounting plate.

The upper gage 86 is particularly effective when sawing a shoe upper of the type illustrated in Fig. 11, having a binding strip 104 wrapped about its edge, which strip requires trimming at its ends after the sewing operation is completed. Where such binding strip is employed, it is necessary to sew the upper to its sock lining before trimming in order to prevent accidental detachment of the ends of the binding strip during the sewing operation. Accordingly, the ends of the binding strip are left projecting at least one-half inch.

To enable passage of the projecting ends on the binding strip through the machine during sewing without interference with the feeding movement, the work engaging end of the upper gage 86 is beveled in advance of the sewing point, as best shown in Figs. 1 and 15. Also the upper end of the work engaging abutment is recessed at 106 (see Figs. 7, 8 and 9) below its work engaging surface. As the projecting end of a binding strip 104 approaches the sewing point it is deflected beneath the upper gage 86 and is received into the recess 106 to present a firm edge along the upper to the upper gage. If the binding strip is of excessive thickness, the upper gage will yield upwardly a short distance, compressing the spring 90 to accommodate the excess.

The serially arranged and alternately acting work clamps in the machine embodying the invention, comprise on the one hand, the nonfeeding presser foot 84, which also acts as a platform gage, and the upper surface of the abutment 70 in advance of the sewing point and in the line of the seam. On the other hand, the work feeding clamp comprises the feed foot 10 provided at its work engaging lower end with the needle guiding perforation. The needle assists also in the feeding movement while engaging the work, the work being gripped between the

feed foot 10 and the feed dog 40 also provided with a needle guiding perforation. Feeding movement is thus imparted to the work by the combined action of the feed foot, the feed dog and the needle, all of the clamping and feeding instruments contributing to provide an arrangement capable of sewing the parts of a high-arch slip-lasted shoe with the stress divided equally between the sock lining and upper. When used to sew a shoe having a platform sole attached to the sock lining, the edges of the parts may be brought into register with each other without localized distortion to such an extent as will cause irregularities in the resulting shoe.

In order to regulate the distance between the line of the seam inserted by the machine from the edge of the pre-cut platform sole, the nonfeeding presser foot 84, which acts as a platform gage, is constructed with an adjustment to enable it to move laterally of the line of the seam. Referring more particularly to Figs. 16 to 19 inclusive, the non-feeding foot is rotatably mounted on a vertical screw stud 108 having an enlarged portion passing through the presser foot 84 into a threaded passage in a block 110 secured to the nonfeeding presser foot bar in place of the presser foot 84 described above. The work engaging and clamping end of the presser foot 84 is capable of swinging movement about the screw stud 108. To secure the presser foot 84 in clamped position, it has an upstanding flange through which passes a pair of set screws 112 engaging a flat surface 114 on the block 110 at either side of the screw stud 108, one stud screw acting to move the presser foot in one direction and the other to move it in the other direction. When both set screws are tightened the presser foot is secured in adjusted position.

To assist insertion or removal of a shoe from the machine, especially where the upper has an edge binding (Figs. 11 and 12), projecting beyond its outer edge, the upper gage 86 is raised as the clamping presser foot 84 is lifted from its work clamping position. To this end the presser foot 84 has projecting from its rearward edge a lug portion 116 disposed beneath a set screw 118 provided with a check nut 120 engaged with a lug on the upper gage 86. When the presser foot 85 is lifted, the lug 116 engages the set screw 118 and the upper gage 86 is raised against the force of its spring 94. Upon insertion of a new shoe in the machine, the upper gage 86 being raised, no interference is met in applying the shoe to the work engaging abutment member 70 in a position where the first stitch will be inserted in the binding strip. As the presser foot 84 is lowered to clamp the work, the upper gage 86 descends with it across the edges of the shoe parts to deflect the binding strip 104 downwardly into the position of Fig. 12.

While the improved machine described and illustrated is of advantage in sewing a high-arch slip-lasted shoe in which a platform sole is attached to the sock lining before sewing, the machine also is extremely beneficial in sewing slip-lasted shoes of the ordinary type having no platform sole for guiding the seam. A benefit in using the machine with the ordinary type slip-lasted shoe lies in increased ease of presenting the shoe to the machine and in more accurately fitting a sewn shoe to a last on which it is to be mounted after sewing. Also, with an ordinary type slip-lasted shoe, permanently distorted shoes are substantially avoided and repair operations to correct excessive distortion are materially reduced.

The nature and scope of the invention having been indicated and an embodiment having been described, what is claimed is:

1. A sewing machine for uniting the registering edges of a shoe upper and a sole member while unsupported by a last, said machine having a vertical work support post, lock stitch forming devices, including a vertical straight eye-pointed needle mounted for reciprocation toward and from the post, a shuttle rotating about an axis extending lengthwise of the post in a position where each loop carried by the needle is engaged by

the shuttle, and two alternately acting work clamps arranged serially along the line of a seam being inserted to grip and feed the shoe parts, in combination with a shoe gripping abutment at the upper end of the post comprising one member of one of the clamps and having a horizontal surface engaging the sewed section of the work beyond the needle and being formed with a span along the seam line beyond the needle of less than one-quarter of an inch and with an abrupt drop of a depth greater than the side height of the shoe upper at the end of the span beyond the needle to clear downwardly curving sections of the sewed shoe parts.

2. A sewing machine for uniting the registering edges of a shoe upper and a sole member while unsupported by a last, said machine having a vertical work support post, lock stitch forming devices, including a vertical straight eye-pointed needle mounted for reciprocation toward and from the post, a shuttle rotating about an axis extending lengthwise of the post in a position where each loop carried by the needle is engaged by the shuttle, and two alternately acting work clamps arranged serially along the line of a seam being inserted to grip and feed the shoe parts, in combination with a shoe gripping abutment at the upper end of the post comprising one member of one of the clamps and having a horizontal surface engaging the sewed section of the work beyond the needle and being formed with a span along the seam line beyond the needle of less than one-quarter of an inch, with a shoe engaging projection extending transversely of the seam line a distance less than one-eighth of an inch and with abrupt drops of depths greater than the side height of the shoe upper at the ends of the span and at the edge of the transverse projection to clear downwardly curving sections of the shoe parts both along the seam line and transversely thereto.

3. A sewing machine for uniting the registering edges of a shoe upper and a sole member while unsupported by a last, said machine having a vertical work support post, lock stitch forming devices, including a vertical straight eye-pointed needle mounted for reciprocation toward and from the post, a shuttle rotating about an axis extending lengthwise of the post in a position where each loop carried by the needle is engaged by the shuttle, and two alternately acting work clamps arranged serially along the line of a seam being inserted to grip and feed the shoe parts, in combination with a shoe gripping abutment at the upper end of the post comprising one member of one of the clamps and having a horizontal surface engaging the sewed section of the work beyond the needle and being formed with a span along the seam line beyond the needle of less than one-quarter of an inch, with a shoe engaging projection extending transversely of the seam line a distance less than one-eighth of an inch and with abrupt drops of depths greater than the side height of the shoe upper at the ends of the span and at the edge of the transverse projection to clear downwardly curving sections of the shoe parts both along the seam line and transversely thereto, said post being cut away to form in the abutment an angular recess including the abrupt drop, of greater width transverse to the seam line at the lower portion of the post beneath the shuttle than at the upper portion of the post near the work engaging surface of the abutment.

4. A sewing machine for uniting the registering edges of a shoe upper and a sole member while unsupported by a stitch last, said machine having a work support post, lock stitch forming devices, including a straight eye-pointed needle mounted for reciprocation toward and from the post, a shuttle rotating about an axis extending lengthwise of the post in a position where each loop carried by the needle is engaged by the shuttle, and two alternately acting work clamps engaging the edges of the shoe parts serially along the line of a seam being inserted to grip and feed the shoe parts, in combination with a stationary abutment at the upper end of the post comprising one member of one of the clamps, said abutment having a

surface engaging the sewed portion of the work both in advance of and beyond the needle with a span along the seam line of less than one-half of an inch and with abrupt drops of depths greater than the side height of the shoe upper at the ends of the span to clear downwardly curving sections of the shoe parts.

5. A sewing machine for uniting the registering edges of a shoe upper and a sole member while unsupported by a last, said machine having a work support post, lock stitch forming devices, including a straight eye-pointed needle mounted for reciprocation toward and from the post, a shuttle rotating about an axis extending lengthwise of the post in a position where each loop carried by the needle is engaged by the shuttle, and two alternately acting work clamps engaging the edges of the shoe parts serially along the line of a seam being inserted to grip and feed the shoe parts, in combination with a stationary abutment at the upper end of the post comprising one member of one of the clamps, said abutment having a surface engaging the sewed portion of the work both in advance of and beyond the needle with a span along the seam line of less than one-half of an inch, with a shoe engaging projection extending transversely of the seam line a distance of less than one-eighth of an inch and with abrupt drops greater than the side height of a shoe upper at the ends of the span and at the edge of the transverse projection to clear downwardly curving sections of the shoe parts both along the seam line and transversely thereto.

6. A sewing machine for uniting the registering edges of a shoe upper and a sole member while unsupported by a last, said machine having a work support post, lock stitch forming devices, including a straight eye-pointed needle mounted for reciprocation toward and from the post, a shuttle rotating about an axis extending lengthwise of the post in a position where each loop carried by the needle is engaged by the shuttle, and two alternately acting work clamps engaging the edges of the shoe parts serially along the line of a seam being inserted to grip and feed the shoe parts, in combination with a stationary abutment at the upper end of the post comprising one member of one of the clamps, said abutment having a surface engaging the sewed portion of the work both in advance of and beyond the needle with a span along the seam line of less than one-half of an inch, with a shoe engaging projection extending transversely of the seam line a distance of less than one-eighth of an inch and with abrupt drops greater than the side height of a shoe upper at the ends of the span and at the edge of the transverse projection to clear downwardly curving sections of the shoe parts both along the seam line and transversely thereto, said post being cut away to form a drop at the end of the span beyond the sewing point in the machine with an angular recess of greater width transverse to the seam line at the lower portion of the post beneath the shuttle than at the upper portion.

7. A sewing machine for uniting the registering edges of a shoe upper and a sole member while unsupported by a last, said machine having a work support post, lock stitch forming devices, including a straight eye-pointed needle mounted for reciprocation toward and from the post, a shuttle rotating about an axis extending lengthwise of the post in a position where each loop carried by the needle is engaged by the shuttle, and two alternately acting work clamps engaging the edges of the shoe parts serially along the line of a seam being inserted to grip and feed the shoe parts, in combination with a stationary abutment at the upper end of the post comprising one member of one of the clamps, said abutment having a surface engaging the sewed portion of the work both in advance of and beyond the needle with a span along the seam line of less than one-half of an inch, with a shoe engaging projection extending transversely of the seam line a distance of less than one-eighth of an inch and with abrupt drops greater than the side height of a shoe upper at the ends of the span and at the edge of the transverse

projection to clear downwardly curving sections of the shoe parts both along the seam line and transversely thereto, said post being cut away to form vertically extending angular recesses of greater widths transverse to the seam line at the lower portion of the post beneath the shuttle than at the upper portion.

8. A sewing machine for uniting the registering edges of a shoe upper and a sole member while unsupported by a last, said machine having a vertical work support post, lock stitch forming devices, including a vertical straight eye-pointed needle mounted for reciprocation toward and from the post, a shuttle rotating about an axis extending lengthwise of the post in a position where each loop carried by the needle is engaged by the shuttle, two alternately acting work clamps arranged serially along the line of the seam being inserted to grip and feed the shoe parts and separate individually adjustable brackets for the work support and shuttle, the work support bracket being cut off shorter at its upper end than the shuttle bracket, in combination with a separate V-shaped work engaging abutment secured to the cutaway upper end of the work support bracket, the smaller end of the V-shaped abutment being uppermost and its lower spaced ends being secured to the upper end of the work support bracket.

9. A sewing machine for uniting the registering edges of a shoe upper and a sole member while unsupported by a last, said machine having a vertical work support post, lock stitch forming devices, including a vertical straight eye-pointed needle mounted for reciprocation toward and from the post, a shuttle rotating about an axis extending lengthwise of the post in a position where each loop carried by the needle is engaged by the shuttle, two alternately acting work clamps arranged serially along the line of the seam being inserted to grip and feed the shoe parts and separate individually adjustable brackets for the work support and shuttle, the work support bracket being cut off shorter at its upper end than the shuttle bracket, in combination with a separate V-shaped work engaging abutment secured to the cutaway upper end of the work support bracket, the smaller end of the V-shaped abutment being uppermost and its lower spaced ends being secured to the upper end of the work support bracket, and a strut connecting the lower spaced ends of the V-shaped abutment.

45. 10. A sewing machine for uniting the registering edges of a shoe upper and a sole member while unsupported by a last, said machine having a vertical work support post, lock stitch forming devices, including a vertical straight eye-pointed needle mounted for reciprocation toward and from the post, a shuttle rotating about an axis extending lengthwise of the post in a position where each loop carried by the needle is engaged by the shuttle, two alternately acting work clamps arranged serially along the line of a seam being inserted to grip and feed the shoe parts, including a presser foot and a feed dog, and separate individually adjustable brackets for the work support and shuttle, the work support bracket being cut off shorter at its upper end than the shuttle bracket, in combination with a separate V-shaped, work engaging abutment secured to the upper end of the work support bracket, said abutment having its smaller end uppermost and its lower spaced ends connected to the work support bracket, and a feed dog receiving slot in the upper smaller end of the abutment, said abutment having inclined sides forming abrupt drops surrounding the feed dog.

11. A sewing machine for uniting the registering edges of a shoe upper and a sock lining to which is attached a smaller-sized platform sole centered on the sock lining to provide projecting marginal edges, said shoe parts being unsupported by a last, said machine having a work support post, and lock stitch forming devices, including a vertical straight eye-pointed needle mounted for reciprocation toward and from the post, in combination with a work clamp arranged to grip the shoe parts being

operated upon along the line of the seam inserted, comprising a presser foot for securing the marginal, projecting edge of the sock lining against the work support and forming a platform sole edge guide, said presser foot having a horizontal nib projecting transversely at one side only from the line of the seam inserted by the needle a distance above the work clamping surface of said foot equal to the thickness of the platform sole to hold the marginal edge of the platform sole in a horizontal position and to cause the platform sole to bend a short distance from its extreme edge, thereby preventing flexure of the sock lining at the edge of the platform sole.

12. A shoe sewing machine for uniting the registering edges of a sock lining and an upper having an edge binding strip projecting beyond the edges of the upper, said machine having a work clamp including a work support arranged to grip the shoe parts along the line of the seam inserted and stitch forming devices including a vertical straight eye-pointed needle mounted for reciprocation toward and from the work support, in combination with an upper gage located at one side of the seam line and formed with a beveled work engaging end to deflect beneath it the projecting end of the binding strip as the edge of the shoe upper approaches the sewing point, and a spring acting on the upper gage for pressing it yieldingly toward the work support to enable the projecting end of a binding strip to be deflected beneath the upper gage as the sewing point is approached, the work support being recessed below its work engaging surface opposite the work engaging end of the upper gage to receive the binding strip as it is deflected beneath the upper gage.

13. A shoe sewing machine for uniting the registering edges of a sock lining and an upper having an edge binding strip projecting beyond the edges of the upper, said machine having a frame, a work clamp including a work support arranged to grip the shoe parts along the line of the seam inserted, stitch forming devices including a vertical straight eye-pointed needle mounted for reciprocation toward and from the work support, said work clamp also including a presser foot movably mounted on the frame to clamp and release the work, in combination with an upper gage located at one side of the seam line and supported on the machine frame for movement toward and from the work support, means acting yieldingly to press the upper gage toward the work support, and means for raising the upper gage as the presser foot is lifted from its work clamping position comprising a portion of the presser foot and means carried by the upper gage engaged thereby when the presser foot is lifted to raise the upper gage from the work support for convenient insertion of the upper.
